UNITED STATES PATENT OFFICE.

DUAYNE L. MATHESON, OF CEDAR CITY, UTAH.

AUTOMATIC FILM REWINDER.

Application filed February 19, 1927. Serial No. 169,502.

The present invention relates to an automatic film re-winder and aims to provide a structure useful particularly in the displaying of motion picture films. It is the common practice to re-wind the film from the take-off roller, this necessitating an additional operation. The present invention does away with this operation as the film is wound in the first instance in proper condition to be immediately disposed.

Another very important object of the invention lies in the provision of a device of this nature which is simple in its construction, inexpensive to manufacture, thoroughly reliable and efficient in operation, easy to manipulate, and otherwise well adapted to the purpose for which it is designed.

With the above and numerous other objects in view as will appear as the description proceeds, the invention resides in the novel features of construction, and in the combination and arrangement of parts as will be hereinafter more fully described and claimed.

25 In the drawings:

Figure 1 is a sectional plan view of the device embodying the features of my invention,

Fig. 2 is an end elevation thereof.

30 Referring to the drawing in detail it will be seen that 5 denotes a stationary shaft, 6 a rotatable shaft having a socket 7 for rotatable mounting on one end of the stationary shaft, said socket being square on the exterior for receiving a drum 8 the rim of which is provided with a transverse slot 9 having a film fastening element 10 immediately adjacent thereto. A stop collar 11 is fixed on the shaft 5 remote from the drum 8. A collar 12 is slidable on the shaft 5, a third collar 14 is slidable on the shaft 5, the collar 14 being disposed at one side of the stop collar 11 and the collar 12 being disposed to the other side thereof. A spring 15 is disposed

45 between the collars 11 and 12 impinging thereagainst and preferably being of the coiled type disposed about the shaft 5. A plurality of arms 16 are pivotally engaged on the collar 12 and have rollers 17 mounted at their outer ends within the drum 8. These rollers being mounted on shafts 18 are held in parallel relationship with the drum 8 by springs 19. Arms 20 are pivotally engaged with the arms 16 as at 21 and with the collars 14 as at 22. The spring 15, therefore, maintains the brackets with their free

ends normally spread apart. A frame 23 is pivotally mounted on one of the arms 16 as at 24 and has journaled therein a roller 25. The film is trained over the roller 25 and then about the roller 17 and then passes through the slot 9 and engages the fastening element 10. The drum is then placed in rotation and the film is wound up inside the drum, the rollers 17 through the assistance of the spring 19 and the arms 16 actuated by the spring 15 through the arms 20 maintaining the film pack thus being formed in a tight condition.

It is thought that the construction, utility, and advantages of this invention will now be apparent to those skilled in this art without a more detailed description thereof. The present embodiment of the invention has been disclosed in detail merely by way of example since in actual practice it attains the features of advantages enumerated as desirable in the statement of the invention and the above description. Obviously, numerous changes in details of construction and in the combination and arrangement of parts may be resorted to without departing from the spirit or scope of the invention as herein-after claimed or sacrificing any of its advantages.

Having thus described my invention, what I claim as new is:

1. A film winding device of the class described including, in combination, a stationary shaft, a rotatable shaft in alinement therewith, a drum on the rotatable shaft having a rim, said drum being provided with a slot in the rim, means on the drum adjacent the slot for anchoring the end of a film which passes through the slot, a collar slidably mounted on the stationary shaft, arms extending from the collar and pivoted thereto, rollers pivoted on the ends of the arms within the rim of the drum to hold layers of the film in tight engagement with each other, a spring means urging said arms outwardly so that the rollers will tighten the film coil pack formed within the drum, guide means on one of the arms for the film adapted to guide said film during the rotation of the drum whereby succeeding layers are placed within preceding layers of said film.

2. A film winding device of the class described including, in combination, a stationary shaft, a rotatable shaft in alinement therewith, a drum on the rotatable shaft having a rim, said drum being provided with

a slot in the rim, means on the drum adjacent the slot for anchoring the end of a film which passes through the slot, a collar slidably mounted on the stationary shaft, arms extending from the collar and pivoted thereto, rollers pivoted on the ends of the arms within the rim of the drum to hold layers of the film in tight engagement with each other, spring means urging said arm outwardly so that the rollers will tighten the

film coil pack formed within the drum, guide means on one of the arms for the film adapted to guide said film during the rotation of the drum whereby succeeding layers are placed within preceding layers of said film, 15 spring means between the rollers and the arms urging said rollers in parallelism with the drum.

In testimony whereof I affix my signature.
DUAYNE L. MATHESON.
